UNITED STATES PATENT OFFICE.

HORACE T. LUSTER, OF BEREAL, OHIO.

THREAD-CABINET.

SPECIFICATION forming part of Letters Patent No. 514,947, dated February 20, 1894.

Application filed March 17, 1892. Serial No. 425,295. (No model.)

To all whom it may concern:

Be it known that I, HORACE T. LUSTER, of Berea, in the county of Cuyahoga and State of Ohio, have invented certain new and useful 5 Improvements in Thread Holders or Cabinets; and I do hereby declare the following to be a full, clear, and exact description of the invention, such as will enable others skilled in the art to which it pertains to make and use the 10 same.

My invention relates to improvements in thread-holders or cabinets, wherein the spools of thread are kept in upright or inclined tubes or holders, adapted to accommodate the 15 spools crosswise and opening into a chute or inclined trough; and my invention consists more especially in mechanism whereby a single spool of thread may be cut off from the row or file of spools in the respective tubes 20 or holders.

My invention consists, also, in certain features of construction and in combination of parts hereinafter described and pointed out in the claim.

25 In the accompanying drawings, Figure 1 is a front-side elevation of a cabinet embodying my invention, portions being broken away and sectioned to more clearly show the construction. Fig. 2 is a side elevation in section, showing a suitable construction of cut-off mechanism. Fig. 3 is a horizontal section, on line 3—3, Fig. 2, illustrative of the cut-off mechanism. Fig. 4 is a plan view of the button for manipulating the cut-off mechanism, 30 said button bearing distinguishing marks, figures, letters, or characters, to indicate the number and the color of the thread contained within the tube or holder with whose cut-off mechanism said button is operatively connected.

40 A represents the casing of the cabinet. Within this casing, at the lower end thereof, are located chutes or inclined troughs, B, that are preferably of sheet metal and supported 45 by slats *a* at the sides of the cabinet and rest upon the bottom of the latter, as at *a'*. The two troughs shown, constitute substantially one trough that is supported at the ends by the slats aforesaid and declines from either 50 end toward the central portion of the cabinet where the trough is provided with an opening, as at *B'*, and the bottom of the cab-

inet is provided with a corresponding opening that registers with the discharge-opening aforesaid of trough or troughs B. Trough or 55 troughs B support upright tubes or holders C. Tubes or holders C are preferably made of sheet metal and soldered to, and opening into, trough B.

The cabinet shown has two tiers of upright 60 tubes or holders C, located the one tier in front of the other with the tubes or holders of the rear tier arranged to "break joints," as it were, with the tubes or holders in the forward tier. As hereinbefore indicated, 55 tubes or holders C are adapted to accommodate the spools of thread crosswise.

Suitable cut-off mechanism is provided for each tube or holder C whereby a single spool of thread may be cut off from the row or file 70 of spools within the respective tube or holder, and allowed to drop into trough B below and slide or roll down the latter to and out of the discharge-opening of the cabinet. T represents the spools of thread. A desirable construction of cut-off mechanism is shown in Figs. 2 and 3 of the drawings, wherein D represents a metallic plate located between the front side of the cabinet and forward tier of tubes or holders, C, plate D extending from side to side of the casing of the cabinet and secured to the latter in any suitable manner. Plate D is provided with rearwardly projecting lugs or ears, *d*, to which is pivoted, respectively, a tilting-lever, E, as at *e*. 80 85

Referring, first, to the cut-off mechanism for the tubes or holders C in the forward tier of tubes or holder, each tilting-lever, E, at opposite ends, has operatively connected therewith, as at *g*, a slide, G, and the upper end of 90 the tilting-lever, adjacent the attachment of the respective slide, has also connected therewith, a rod, H, the latter extending forward through perforations in plate D and the front side of the cabinet, respectively, and terminating outside of the cabinet in a button, I. Slides G of the cut-off mechanism of tubes or 95 holders C are located a distance apart approximately equal to the diameter of the spool of thread that the respective tube or holder is designed to carry, and the tube or holder, a corresponding distance apart, is slotted horizontally preferably both at the front and at either side, as at *c c' c'*.

Slots $c c' c'$ are adapted to accommodate the passage of slides G in and out of tube or holder C and the bottom walls of slots $c c'$ afford ample bearing for the respective slides, 5 the latter extending preferably somewhat at either side of the respective tube or holder, as shown at G', Fig. 3. By the construction just described, slides G will adequately support the row or file of spools of thread with- 10 out liability of being deranged by the weight of the spools of thread or otherwise, and ex- tending somewhat at either side of the re- spective tube or holder, as aforesaid, they are not likely to be displaced from the bearing 15 afforded by the bottom walls of the slots $c c'$.

Rod H at the rear of the front side of the cabinet is provided with a pin or shoulder, h , and upon rod, H, between pin or shoulder, h , and the front side of plate, D, is mounted and 20 confined, a spring, J, preferably a coil-spring, as shown, said spring acting in the direction against pin or shoulder, h . The arrangement of parts is such, that in the normal position of the cut-off mechanism, with pin or shoul- 25 der, h abutting the adjacent surface of the front wall of the cabinet, upper slide G will be practically withdrawn from the respective tube or holder, and the lower slide G, will be in position supporting the file of spools of 30 thread, as shown more clearly in Fig. 2. If it is now desired to cut off a spool of thread from the file of spools in the respective tube or holder, this can readily be effected by the required pressure of the thumb, or finger, of 35 one hand upon button, I, in the direction to compress spring J. The upper and lower slides will be moved in opposite directions, the upper slide being brought into a position to hold back and support all but the lower- 40 most spool of thread, and the lower slide being withdrawn from the tube or holder suffi- ciently far to release the lowermost spool in the tube or holder, and permit the same to drop into trough, B, below, the spool, thus re- 45 leased, rolling or sliding down said trough to the discharge-opening of the cabinet, where it is caught by the operator, the latter having his other hand in readiness for the purpose. Upon removing the pressure of the thumb or 50 finger from button I, the cut-off mechanism will, by the action of spring J, be returned to its normal position, withdrawing the upper slide, and bringing the lower slide in position to support the spools within the respective 55 tube or holder, the row or file of spools of course advancing the distance that was occupied by the spool discharged.

The cut-off mechanism for the rear tier of tubes is substantially the same as that al- 60 ready described, excepting that rod H, is ex- tended through the space between the adja- cent tubes or holders of the forward tier, and instead of tilting-lever E, being connected directly to the respective slides, the upper 65 end of the tilting-lever is pivoted to rod H, as at g^2 , and the lower end of the respective tilting-lever is pivotally connected with the

lower slide by means of a link, K. There is, of course, sufficient space between the tubes or holders of the forward tier of tubes or 70 holders, and between the forward and rear tiers of tubes or holders, to accommodate the operation of the cut-off mechanism of the tubes or holders at the rear.

The tubes or holders, and the cut-off mech- 75 anism, excepting buttons, I, and the forward end of rods H, are of course invisible from outside the cabinet, and as the tubes or hold- 80 ers, C, are of different sizes, and accordingly are designed to receive coarser or finer thread, as the case may be, and thread of a certain color, some suitable means should be pro- 85 vided, whereby the different threads (refer- ring to color and to number of fineness or coarseness) may be readily located.

In the drawings is illustrated a cabinet de- 90 signed for black and white thread, the tubes or holders at one side of the cabinet, being designed to receive the black thread, and the tubes or holders at the other side of the cab- 95 inet being designed to receive white thread. As shown more clearly in Fig. 4, I provide the face of buttons, I, with a figure or figures to correspond with the number of thread con- 100 tained within the tube or holder with whose cut-off mechanism the respective button is operatively connected, and I employ black and white figures, according as the thread is black or white.

Referring again to Fig. 4 button I that 100 bears figure 9 in white upon a black back- ground, would indicate that the tube or holder with whose cut-off mechanism said button was operatively connected, contained white thread No. 9, (the number indicating the 105 quality of thread as to coarseness or fineness) whereas button I that bears figure 9 in black upon a white back-ground, would indicate that the tube or holder with whose cut-off mechanism said button was connected, con- 110 tained black thread No. 9.

What I claim is—

In a thread-cabinet, a chute or inclined trough in open relation with the outside of the cabinet, and two tiers of upright holders located the one tier forward of the other, with the holders of the one tier arranged to break joints with the holders of the other tier, and with the holders of both tiers of holders in open relation with said trough or chute, in 115 combination with cut-off mechanism for each tube or holder, said cut-off being adapted to be operated from outside the cabinet and adapted to release a single spool of thread from the respective holder and permit the 120 spool to fall into said chute or trough, sub- stantially as set forth.

In testimony whereof I sign this specifica- 125 tion, in the presence of two witnesses, this 27th day of January, 1892.

HORACE T. LUSTER.

Witnesses:

C. H. DORER,
WARD HOOVER.
